(57) **CLAIM**

We claim the ornamental design for a bicycle cradle, as shown and described.

DESCRIPTION

FIG. 1 is a perspective view of a bicycle cradle;

FIG. 2 is an upper perspective view of a bicycle cradle;

FIG. 3 is a lower perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

The broken lines are directed to environment and are for illustrative purposes; the broken lines form no part of the claimed design.
